JOSEPH F. HORNING, OF CINCINNATI, OHIO

BINDING FEEDER

Application filed February 25, 1927. Serial No. 170,973.

My present invention has reference to an attachment for sewing machines and has for its object the provision of means whereby a binding tape can be accurately fed from a suitable roll and effectively stitched by the machine to the edges of a fabric.

A further object is the provision of a means for this purpose that can be readily attached to the arm of a head of a sewing machine, and which includes a roll or spool on which a binding tape is wound and trained through a suitable guide that is adjustably associated with the improvement, and whereby the tape may be readily stitched by the machine to the edges of a fabric, regardless of the irregularities of such edges and in a manner most convenient to the operator of a sewing machine.

A further object is the provision of a binding feeder attachment for sewing machines, which includes a bracket to be removably attached to the arm of the head of the machine and which has journaled on its outer end a tape carrying spool or roll, friction means being provided for preventing the free turning of the roll or spool, swingable and vertically adjustable means being carried by the bracket for a guide through which the binding tape is fed in a manner to permit of the said tape being folded upon itself and arranged over the edges of the fabric on which it is stitched by the machine.

To the attainment of the foregoing and other objects which will present themselves as the nature of the invention is better understood, the improvement also resides in certain other novel features of construction, combination and operative association of parts, one satisfactory embodiment of which is disclosed by the accompanying drawings.

In the drawings,

Figure 1 is a perspective view of my improvement in applied position.

Figure 2 is a side elevation of the improvement.

Figure 3 is a top plan view thereof.

Figure 4 is an edge view thereof.

Figure 5 is a sectional view through the roll or spool to illustrate the manner by

which it is removably secured on its supporting shaft.

Figure 6 is a perspective view of one of the spools or cores on which the tape is wound.

Referring now to the drawings in detail the numeral 1 designates the table of an ordinary sewing machine, 2 the head thereof, 3 the presser foot, 4 the needle carrying bar. On the horizontal portion or arm 5 of the head 2 I arrange the bifurcated or jaw end 6 of a bar 6. The clamp or bar 6 has its jaw end provided with an inner facing of compressible material so as not to inflict injury to the head of the machine, and the upper arm of the jaw has threaded therethrough a binding bolt 7 whereby to effectively sustain the clamp on the arm 5 of the head 2. If desired there may be arranged in the jaw end of the clamp a spring member on which the compressible facing is arranged. The clamp has an angle outer end 6'. 55 60 65

Screwed through the outer end 6' of the clamp there is the threaded portion of a shaft 8. Screwed on the shaft, and contacting with the end 6' of the clamp there is a combined jamb nut and washer 8'. The shaft 8 has its outer end provided with a continuous groove 9 that is designed to receive therein a pivotally supported spring latch 11 carried by the outer member or flange of the spool 10. The spool 10 comprises two members, each having an inner hub portion 10' through which the shaft 8 passes. Opposite the hub the inner face of the members comprising the spool 10 have lugs 25, and these lugs are designed to be received in notches 26 on the ends of the spool or core 27 on which the tape is wound. Usually the tape is of two widths and, of course, the cores 27 are of widths corresponding to that of the 70 75 80 tapes and by a construction as that just described it will be apparent that the adjustment of the shaft 8 through the end 6' of the clamping member, and the adjustment of the jamb nut 8' on the shaft, permits of the arrangement of different sized cores 27 between the elements constituting the spool 10. 85

Of course, the outer element of the spool is removed before the core is arranged on the hubs 10' of the said spool sections. 90 95 100

Fixed by means 12 on the upper edge of the clamp 6 there is a flat arched spring 13. The outer curved end of this spring rests directly on the periphery of the inner member of the spool 10. The tension of the spring 13 is adjusted through the medium of a headed screw member 13' that passes through an opening in the spring 13 and is received in a threaded opening in the clamp member 6. By this arrangement it will be seen that the spool 10 will be held from free turning.

Pivottally supported by an adjustable and removable element 14 on one side of the clamp 6 there is a curved arm 15 which is directed 15 toward the front of the head 2. Passing through a suitable opening in the outer end of the arm 15 there is a headed screw 16 which is engaged by a mill nut 17. The screw passes through an elongated slot in a plate 18 and is, 20 of course, adjustable on the arm 15.

Also passing through the slot in the plate 18 there is a second headed screw 19 which is engaged by a mill nut 20. The screw passes through the upper end of a twisted plate 21, 25 the lower end of the said plate being formed with or having secured thereon a guide eye 22 for the tape 23 that is fed from the spool 10. It is to be noted that the arm 15 is swingably 30 attached to the clamp 6; that the plate 18 is both vertically adjustably and swingably attached to the arm 15, and that the eye carrying plate 21 is both vertically and swingably attached to the plate 18, and that by virtue of such arrangement the eye 22 may be properly 35 positioned with respect to the edges of the fabric 24 on which the tape is to be stitched, and likewise that the eye can be thus properly positioned upon varying types of sewing machines.

40 The tape 23 may be centrally folded before passing through the guide eye 22 and by properly adjusting the eye with respect to its support or with respect to the operator of the machine the said tape can be arranged on the 45 edges of the fabric, regardless of irregularities in such edges and easily and effectively as well as properly stitched on such edges in a manner most convenient to the operator. Of course different spools containing different 50 lengths of tape may be arranged on the stub shaft 8, and spools containing two windings of binding tape may be also employed. As previously stated only one satisfactory embodiment of the improvement is herein set 55 forth and therefore it is to be understood that I hold myself entitled to make such changes and modifications therefrom as fall within the scope of what I claim, providing, of course that such changes or modifications do 60 not exceed the scope of the claims or depart from the spirit or sacrifice any of the advantages of the invention.

Having described the invention I claim:

65 1. A sewing machine attachment for facilitating feeding of binding tape to the ma-

chine, comprising a bracket adapted to be mounted upon the head of a sewing machine, means on the bracket for supporting a spool carrying binding material, an arm mounted upon and depending from said bracket, a longitudinally slotted link disposed against the lower end of said arm, a clamping screw provided with a nut carried by said arm and passing through the upper end of the slotted link, a vertically arranged tape guide, a twisted link carrying the binding tape guide, and a second clamping screw provided with a nut passing through said twisted link and through the lower end of the slotted link.

2. In a sewing machine attachment for facilitating feeding of binding tape to the sewing machine, a bracket adapted to be mounted upon the head of the sewing machine, means on the bracket for supporting a spool carrying binding material; an arm mounted on said bracket, a link pivotally and longitudinally adjustably connected with the lower end of said arm and swingable vertically in a direction at right angles to the plane of the swinging movement of said arm, a second link pivotally and adjustably mounted upon said first named link and swingable in the same plane therewith, said second named link having its lower end twisted at right angles, and a guide carried by the lower end of the second named link for guiding the binding tape.

In testimony whereof I affix my signature.
JOSEPH F. HORNING.
